Howson & Howson

UNITED STATES PATENT OFFICE.

WILLIAM C. NENSTIEHL, OF WILMINGTON, DELAWARE, ASSIGNOR TO SELF SEAL CONTAINER MFG. COMPANY, INC., OF WILMINGTON, DELAWARE, A CORPORATION OF DELAWARE.

SPRINKLER TOP FOR CONTAINERS.

Application filed January 18, 1926. Serial No. 82,046.

This invention relates to certain improvements upon the sprinkler top for containers set forth in the patent granted to me on the 23rd day of November, 1915, No. 1,161,718.

5 The object of the present invention is to so design the top that the sliding valve will be held tightly to its seat at all times, and to dispense with holding means projecting through the valve, substituting therefor a 10 ring connected to the spring members of the valve. The invention also relates to certain details of construction described hereinafter.

In the accompanying drawing:

15 Fig. 1 is a perspective view of a container showing the improved sprinkler-top;

Fig. 2 is a plan view;

Fig. 3 is a side view;

20 Fig. 4 is a vertical sectional view on the line 4—4, Fig. 2, showing a packing disk;

Fig. 5 is a side view partly in section on the line 5—5, Fig. 2, showing the valve in the open position.

25 Fig. 6 is a perspective view of the packing disk; and

Fig. 7 is a sectional view similar to Fig. 4, in which the packing disk between the valve and its seat is omitted.

The body 1 of the container can be of any 30 form desired. The cap 2 has a deep flange in the present instance, and projecting from the cap is a tubular extension 3, forming a valve seat. In the valve seat are perforations 4.

35 A valve 5 is mounted on the valve seat at the end of the projection, and in the valve are perforations 6 which are arranged to align with the perforations 4 in the seat when moved to one side, as in Fig. 5.

40 When the valve 5 is in its normal position, the solid portions of the valve close the perforations 4 in the seat, preventing the escape of the contents of the container.

The valve is in the form of a flat sheet 45 metal plate. In order to prevent the valve turning on its seat, a rib 7 is formed on the seat, and the valve is grooved as at 8 by pressing the metal to receive the rib, so that while the cap can slide freely in one direction, it cannot turn.

At opposite sides of the valve 5 are tongues 9, which are shaped to form springs. These tongues are connected to a ring 10. The tubular extension 3 has an annular groove 11,

formed therein to receive the ring 10. The 55 upper wall of the groove forms a shoulder, retaining the ring in position and holding the valve close to its seat, and the spring-tongues fulcrum at the ring, so that when either tongue is pushed, as indicated by the 60 arrow, Fig. 5, both tongues yield, allowing the valve to move to one side and uncover the perforations 4 in the seat. As soon as the valve is released, the spring-tongues return 65 the valve to its normal closed position.

The valve ring and spring-tongues are preferably made integral either by forming a cup-shaped blank and cutting the parts by suitable dies, or by stamping the parts flat and then bending them to shape, the end 70 of the blank forming the ring being connected after being applied to the extension of the cap. A packing disk 12 is preferably located between the valve and its seat, as shown in Fig. 4, the seat being depressed to receive 75 the disk, which is shaped as shown in Fig. 6, and has a slot therein for the rib 7 on the seat. This disk may be of paper, felt or similar material to form a packing between the valve and its seat.

I claim:

1. The combination of a container having a perforated seat and having an annular groove some distance below the seat; a perforated valve arranged to slide on said seat; a retaining ring located in the groove; and a spring-tongue connecting the ring with the valve.

2. The combination of a container having an extension provided with a perforated 90 seat and having an annular groove some distance from the seat; a perforated valve mounted on the seat; a ring located in the groove; and two spring-tongues connecting the valve to the ring.

3. The combination of a container; an extension thereon having a shoulder; a perforated valve seat at the end of the extension; a perforated valve mounted on the seat; a ring encircling the extension and 100 bearing against the shoulder; oppositely disposed spring-tongues connecting the valve to the ring; and means for preventing the valve turning on the seat, the perforations in the valve being out of line with those on the seat 105 when the valve is in its normal position.

4. The combination of a container having a perforated valve seat, said seat being de-

pressed; a packing disk located in the depression and having perforations aligning with those in the seat; means for preventing the packing disk from turning; and a perforated valve mounted on the end of the container and having spring tongues attached at their ends to the container.

5. The combination in a container, of a flat perforated sheet metal seat, having a

central transverse guiding rib formed thereon; and a perforated valve mounted to slide on said seat and having a groove to receive the rib, so that the valve is guided by the rib, the valve having a spring-tongue, said tongue being attached to the container some 15 distance from the seat.

WILLIAM C. NENSTIEHL.
